MOTOR UNIT FOR MAGNETIC STIRRER

Leonard Bezark, Jr., Highland Park, Ill., assignor to
La Pine Scientific Company

Filed Jan. 20, 1964, Ser. No. 78,256

Term of patent 14 years

(Cl. D55—1)

Fig. 1

Fig. 2

FIGURE 1 is a perspective view of a motor unit for a magnetic stirrer embodying my design;

FIGURE 2 is a top plan view thereof;

FIGURE 3 is a side elevation looking from the right of FIGURE 2;

FIGURE 4 is a rear elevation;

FIGURE 5 is a front elevation; and

FIGURE 6 is a bottom plan.

The essential features of the design reside in the combination on a motor unit of the configuration shown of the particular form and arrangement of inset panel with the particular control knob shown and the particular tab below the knob, centrally located at the lower edge of said panel and extending below the bottom thereof.

I claim:

The ornamental design for a motor unit for magnetic stirrer, as shown and described.
